UNITED STATES PATENT OFFICE.

HARRY H. WEST, OF PLYMOUTH, PENNSYLVANIA.

MACHINE FOR FORMING TATTING-BRAID

1,313,439.

Specification of Letters Patent.

Patented Aug. 19, 1919.

Application filed July 3, 1918. Serial No. 243,167.

To all whom it may concern:
Be it known that I, HARRY H. WEST, a citizen of the United States, residing at Plymouth, in the county of Luzerne and State of Pennsylvania, have invented certain new and useful Improvements in Machines for Forming Tatting-Braid; and I do declare the following to be a full, clear and exact description of the invention, such as will enable others skilled in the art to which it appertains to make and use the same.

My invention has for its principal object the provision of a machine which will make possible the rapid production of tatting, the present machine serving to form a chain of interlooped loops which may be connected at longitudinally spaced points to form the rings of the tatting, and these rings may be in turn connected in numerous ways to produce different designs. In carrying out this end, a thread which I term a body thread is supported between two points, a shuttle is passed alternately over and under this body thread to loop the shuttle thread around the same, and said shuttle thread is looped in the path of the shuttle to cause interlooping of the several loops passed around the body thread.

Further objects are to provide for the automatic raising and lowering of the shuttle to pass it first over and then under the body thread, and to make provision for allowing the shuttle to move freely across the body thread without danger of breaking the latter.

Yet another object is to provide novel thread manipulating means for looping the thread alternately up and down in the path of the shuttle.

A still further object is to provide a highly efficient and durable, yet a simple and comparatively inexpensive machine for obtaining the required results, and to so construct the device as to permit effective operation thereof without continual manual attendance.

With the foregoing objects in view, the invention resides in the novel features of construction and unique combinations of parts to be hereinafter fully described and claimed, the descriptive matter being supplemented by the accompanying drawings which form a part of this specification and in which:

Figure 1 is a side elevation, partly in section, of the machine;

Fig. 2 is a vertical transverse section on the plane indicated by the line 2—2 of Fig. 1;

Figs. 3 and 4 are horizontal sections on the planes indicated by the lines 3—3 and 4—4 respectively of Fig. 1;

Figs. 5 and 6 are detail vertical transverse sections on the planes designated by the lines 5—5 and 6—6 of Fig. 1;

Fig. 7 is a view similar to Fig. 1 but illustrating a different position of parts;

Fig. 8 is a transverse section of Fig. 7 on the plane of the line 8—8 thereof showing more clearly the positions of the thread manipulating arms;

Fig. 9 is a fragmentary view similar to Fig. 7 but illustrating still another stage in the operation of the machine;

Fig. 10 is a transverse section of Fig. 9 on the plane of the line 10—10 thereof;

Fig. 11 discloses a further phase in the operation of the machine;

Fig. 12 is a transverse section on the plane of the line 12—12 of Fig. 11;

Fig. 13 is a view identical with Fig. 11 with the exception that it discloses the manner in which one of the thread manipulating arms forces laterally on the thread to tighten a previously formed loop;

Fig. 14 is a vertical section on line 14—14 of Fig. 13;

Fig. 15 is a side elevation similar to those above described but showing different position of parts;

Fig. 16 is a transverse section on the plane of the line 16—16 of Fig. 13;

Figs. 17 and 18 are side elevations showing still other stages of the operation;

Fig. 19 is a side elevation of the cam drum;

Fig. 20 is an end elevation thereof;

Figs. 21, 22, 23 and 24 are transverse sections on the planes of the lines 21—21, 22—22, 23—23 and 24—24 respectively of Fig. 19;

Fig. 25 is an elevation of the braid produced by the machine;

Fig. 26 is a top plan view of the shuttle;

Fig. 27 is a side elevation thereof;

Figs. 28 and 29 are respectively vertical longitudinal and vertical horizontal sections on the planes indicated by the lines 28—28 of Fig. 27 and 29—29 of Fig. 26;

Figs. 30 and 31 are transverse sections on the planes of the lines 30—30 and 31—31 of Fig. 29;

Fig. 32 is a side elevation of the thread manipulating means for looping the shuttle thread upwardly;

Fig. 33 is a horizontal section on the line 5 33—33 of Fig. 32;

Fig. 34 is a side elevation of the manipulating means for looping the thread downwardly;

Fig. 35 is a horizontal section on the line 10 35—35 of Fig. 34;

Fig. 36 is a detail longitudinal section of a portion of the shuttle and a side elevation of a portion of the shuttle holding means; and

15 Fig. 37 is a transverse section on the plane of the line 37—37 of Fig. 36.

Briefly speaking, the present machine consists of means for supporting a body thread, feeding means for the thread, a shuttle movable across said body thread at one side thereof and movable reversely across the body thread at its other side, means for operating the shuttle in the required manner, and thread manipulating arms for looping 25 the shuttle thread in the path of the shuttle. The machine may be specifically described as follows:

A table 1 is supported on legs or the like 2 and is shown provided at one end with a 30 pair of supports 3 having eyes 4 to receive the body thread B, said supports being preferably though not necessarily so located as to position the thread B obliquely of the table 1. The supports 3 are located adjacent 35 one end of the table and a bracket 5 rises from the other end thereof, one end of a vertically swinging carriage support 6 being pivoted at 7 to said bracket. The support 6 is provided adjacent its upper edge 40 with a longitudinal track 8 and near its lower edge with flanged rollers 9, said track and rollers slidably supporting a horizontally elongated carriage plate 10 for the shuttle 11. A vertical push rod 12 slides through 45 a guide 13 on the table 1 and is provided at its lower end with a roller 14 coacting with a cam 15 on a cam drum 16 which is driven in the manner yet to be described to alternately raise and lower the rod 12 to similarly move the support 6 and the shuttle carriage 10.

One end of the carriage 10 is forked, and the shuttle 11 is loosely received between the arms 17 of the fork, said shuttle being by 55 preference of the cylindrical shape shown, with conical ends. As will hereinafter appear, it is necessary to provide means for first holding one end of the shuttle 11, and then releasing said end while gripping the 60 other end, in order to permit the shuttle to pass entirely across the body thread B. For obtaining this result, the shuttle holding means shown is preferable, this means consisting of a pair of levers 18 fulcrumed between their ends at 19 to the fork arms 17,

said levers having inwardly extending plugs 20 on opposite sides of their fulcrums and receivable in sockets or slots 21 with which the ends of the shuttle 11 are provided (see Figs. 26 to 31, 36 and 37). To prevent the 70 thread B from catching on the plugs 20, thread guards 22 by preference extend from the levers 18 on opposite sides of said plugs and bear against the shuttle as shown most clearly in Fig. 37. A coiled spring 23 connects the inner ends of the levers 18 and normally retains the rearmost shuttle holding means in operative position (see Fig. 1), but by the means now to be described, said levers may be rocked against the tension of 80 the spring in question to apply the front holding means to use.

A longitudinal arm 24 is pivoted at 25 to the carriage 10 and rests at its front end upon the inner end of the lowermost lever 85 18, while an actuating lever 26 bears against the inner end of the upper lever 18 and is fulcrumed at 27 to the carriage plate, the rear end of said actuating lever having a depending shouldered lug 28 whose shoulder 90 rests on the arm 24, and an upstanding lug or strike 29 coöperating with a fixed trip plate 30 secured to the front end of the support 6 (see for instance Fig. 9). By this arrangement, when the carriage 10 is forced 95 forwardly, the strike 29 comes in contact with the trip 30 at the proper time and quickly reverses the positions of the levers 18, so as to apply the front holding means to the shuttle, rather than the rear holding 100 means. It will of course be understood that this change takes place when the thread B is located between the front and rear holding means 20.

Any suitable means could be provided for 105 reciprocating the shuttle carriage 10, but I preferably employ a vertical throw lever 31 having its upper end received between rollers or the like 32 carried on the carriage, while the lower end of said lever is fulcrumed to a suitable part, such as one of the legs 2. A pitman 33 connects lever 31 with a crank arm 34 on a transverse shaft 35, and a train of gearing 36 is provided for driving the shaft 37 of the drum 16, from 110 said shaft 35, at half the speed of the latter. Shaft 35 is preferably provided with a hand wheel 38 for initially setting the machine before running under power, and said shaft is also equipped with tight and loose pulleys 115 39 and a belt 40 which may be provided with a belt shifter 41 as shown. This driving means is by preference followed, but it will be obvious that any means could well be employed for obtaining the same results. 125

For supporting and feeding the body thread B, any preferred means could of course be utilized, and the drawings are typical of one manner in which this may be attained. A spool or reel 42 is mount- 130

ed on the upper end of a standard 43 rising from the table 1, suitable tension means 44 being provided to prevent rapid rotation of the spool. A drum 45 is supported by a 5 suitable standard 46 rising from the table and is intermittently fed by the means to be described. The body thread, and in fact the thread looped thereon, in other words the complete braid, is wound one or more times 10 around the drum 45, depends therefrom, and is provided with a weight 47 to hold the thread B taut. By means of suitable gearing 48, the upper end of a vertical shaft 49 is connected with the drum 45, the lower end 15 of said shaft having a ratchet 50 coacting with the adjustable nose 51 of a reciprocating dog 52 mounted on the table 1 and provided with a lateral finger 53 disposed in the path of the throw lever 31, whereby each 20 forward stroke of said lever will not only shift the carriage 10 forwardly, but will so move the dog as to feed the braid sufficiently to expose a new length of the body thread B for the formation of loops thereon. A 25 spring 54 is provided for returning dog 52 after each forward movement thereof.

The shuttle 11 in moving to and fro across the body thread B in the manner above mentioned, loops the shuttle thread S around 30 said body thread, and in order that the several loops may be interlooped, a pair of vertically swinging thread manipulating arms 55 and 55' are provided, the free ends of said arms having crotches 56 and 56' for engaging 35 with the thread S. The shape and mounting of the arms 55 and 55' are shown more particularly in Figs. 32, 33, 34 and 35, while their manner of operation is illustrated in other views. The arms in question 40 are pivoted at 57 and 57' respectively to supports in the form of bell crank levers 58 and 58', said levers being fulcrumed at 59 and 59' to supporting blocks or the like 60 and 60' carried by the table 1. Fulcrumed be- 45 tween its ends on the fulcrum 59 of lever 58, is a short horizontal lever 61, one end of this lever being connected by a vertical link 62 with the inner end of arm 55; and another short horizontal lever 61' is fulcrumed 50 at one end upon the fulcrum 59' of the lever 58', a link 62' extending from said lever 61' to arm 55'. Vertical actuating links 63 are pivoted to and depend from the levers 58, 58', 61, and 61', the lower ends of all of said links 55 being connected to rocker arms 64 having rollers 65 to travel on actuating cams carried by the drum 16, these cams being shaped according to the work to be accomplished. A 60 series of springs 66 are employed to normally move the rocker arms 64 downwardly to engage the rollers 65 thereof effectively with the cams.

For the construction and arrangement of the cams see more particularly Figs. 19 to 24. 65 The cam for operating the lever 58 through

the instrumentality of the connections above described, is designated at 67 and is detailed in Fig. 21; the cam for link 62 is illustrated at 68 and its precise shape is disclosed in Fig. 22; the cam of lever 62' is detailed at 70 69 in Fig. 23; that for operating link 58' is disclosed at 70 (see Fig. 23); and the shape of cam 15 above described, is disclosed most clearly in Fig. 20, in which the relation of the several cams, disposed one behind the 75 other, is also shown.

A description of the shuttle 11, reference being had more particularly to Figs. 26 to 31, will complete the detailed description of the machine, after which an exposition of its 80 operation will follow. The shuttle is of hollow formation with a bobbin spindle 75 therein carrying a bobbin 76 from which the shuttle thread S is unwound, said thread passing through suitable guide openings 77 85 in the side of the shuttle and then through a guide tube 78 carried by one removable end 79. A bayonet slot and pin connection 80 is provided for retaining the end 79 in place, and when said end is removed, the 90 bobbin may be removed, or replaced as required. When the end 79 is in place, the bobbin 76 is held under sufficient friction to control the unwinding of the thread S by means of a coiled spring 81. Preferably, but not 95 necessarily, an opening 82 is formed through the shuttle end 79 for the reception of a suitable tool, whereby said end may be more easily turned to release the connection 80. The type of shuttle shown and described is by 100 preference employed, but other forms could well be used should occasion so demand.

The operation of the machine is as follows:

We will assume that the machine stands as 105 shown in Fig. 1, that some of the braid has been formed upon the body thread B, and that the shuttle thread S is in the crotch 56 of the arm 55. When the arm stands in the position shown, the carriage support 6 is in 110 horizontal position and the carriage 10 is fully retracted. It will also be observed that shuttle 11 is held by the innermost plugs 20. When lever 31 now operates, the carriage 10 moves forwardly to the position 115 of Fig. 7 to locate the body thread B between the upper lever and the front end of the shuttle 11, the holding means of said bobbin and the position of the support 6, still remaining the same, as does also the 120 arm 55, the other arm 55' remaining idle also and now performing no operation upon the thread S. Still further movement of the carriage 10 causes the strike 27 to abut the trip 30 (see Fig. 9) and at the same time, 125 the cam 15 has come into play to raise the support 6. The moment strike 27 and trip 30 come in contact, the levers 18 are reversed to grip the front end of the shuttle instead of the rear end thereof, the change taking 130

place when the body thread B is located between the front and rear shuttle holding means. It will thus be obvious that the shuttle can travel forwardly beyond the body thread without engaging the same and bowing it, and consequently there is no danger of breaking said thread. The raising of the support 6 to the position shown in Fig. 9, does not take place until after the shuttle 10 has passed forwardly beyond the body thread, and by the time this raising takes place, the crank 34 is in position to return the throw lever 31 to similarly return the carriage 10 to move the shuttle 11 back through the loop L formed by the thread manipulating arm 55 (see Fig. 11), said arm having in the meantime lowered clear of said loop. Return of the shuttle 11 over the body thread B and through the loop L produces the result depicted in Fig. 11, and the arm 55' now moves suddenly forward as will be clear from Figs. 11 and 13, pushing the thread S laterally to tighten the loop. As the carriage 10 now again moves forwardly, with the support 6 still in an inclined position, (see Fig. 15) arm 55' moves downwardly, forms a loop L' of the shuttle thread S and releases this loop. The shuttle then passes over the body thread, the interchange 30 of the arms 18 taking place as above set forth, is lowered by the support 6 to the position of Fig. 17, moves rearwardly through the loop L' as shown in Fig. 18, the interchange of the levers 18 again occurring, and thus forms another loop on the body thread B, said loop being interlooped with the loop previously formed. By this time, arm 55 is again ready to operate to raise the shuttle thread to the position depicted in 40 Fig. 1, thus completing one cycle of operation. The successive cycles are the same and obviously need not be described.

From the operations above set forth, it will be seen that a chain or braid of loops L and 45 L' is formed, these loops being passed around the body thread B and interlooped (see Fig. 25). It is intended that longitudinally spaced points of this chain or braid shall be connected to form the rings of the 50 tatting, but these rings shall be connected, and in fact that the chain or braid in question shall be used to form all sorts of tatting designs such as those now carried out by hand. This may all be done by machine operations forming no part of the present invention.

From the foregoing, taken in connection with the accompanying drawings, it will be seen that although I have produced a simple 60 and inexpensive machine, it will be highly efficient and durable, and will require little attention. Since good results have been obtained from the arrangement shown and described, this arrangement may well be fol-

lowed, but I wish it understood that I have 65 illustrated only one of the many ways in which the machine may be constructed, and that I am not restricted to the exact details shown.

I claim:

1. In a machine for forming tatting braid, means for supporting a body thread, means for carrying an additional thread around said body thread, and means for looping said additional thread and disposing the loops in 75 position for said carrying means to pass therethrough.

2. In a machine for forming tatting braid, means for supporting a body thread, means for carrying an additional thread alternately in opposite directions around said body thread, and means for looping said additional thread and disposing the loops in position for said carrying means to pass therethrough.

3. In a machine for forming tatting braid, the combination of means for supporting a body thread, a thread carrying shuttle movable across said body thread at one side thereof and movable reversely across said body thread at the other side thereof to loop the shuttle thread around said body thread, and thread manipulating means for looping the shuttle thread in the path of said shuttle.

4. In a machine for forming tatting braid, the combination of means for supporting a body thread, means for carrying a second thread to and fro across said body thread, means for relatively shifting said body 100 thread and said carrying means to loop said second thread around said body thread, and thread manipulating means cooperating with said thread carrying means for interlooping the loops of said second thread.

5. In a machine for forming tatting braid, the combination of means for supporting a body thread, a thread carrying shuttle, means for advancing and returning said shuttle across said body thread, thread manipulating means for looping the shuttle thread in the path of the shuttle, and means for shifting said shuttle and body thread relatively between strokes to loop said shuttle around said body thread.

6. In a machine for forming tatting braid, the combination of means for supporting a body thread, a thread carrying shuttle, means for moving said shuttle to and fro across said body thread, including holding 120 means for both ends of the shuttle and means for alternately applying said holding means to permit free passage of said shuttle past said body thread, means for shifting said shuttle and said body thread relatively 125 to loop the shuttle thread around the latter, and means for looping said shuttle thread in the path of said shuttle.

7. In a machine for forming tatting braid, the combination of means for supporting a body thread, a movable support adjacent said thread, a shuttle carriage mounted on 5 said support, a thread carrying shuttle mounted on said carriage, means for operating said carriage to move said shuttle to and fro across said body thread, means for shifting said support at an angle to the 10 movement of said carriage to loop the shuttle thread around said body thread, and means for looping said shuttle thread in the path of said shuttle.
8. In a machine for forming tatting braid, the combination of means for supporting a body thread, a movable support adjacent 15 said thread, a carriage mounted on said support, means for moving said carriage to and fro at an angle to the movement of said 20 support, a thread carrying shuttle, holding means for both ends of said shuttle mounted on said carriage, means for alternately applying said holding means to opposite ends of the shuttle to permit free passage 25 of the latter across said body thread, means for shifting said support between strokes of said carriage to loop the shuttle thread around said body thread, and means for looping said shuttle thread in the path of 30 the shuttle.
9. In a machine for forming tatting braid, the combination of means for supporting a body thread, a support mounted pivotally with its free end adjacent said body thread, 35 a carriage mounted for longitudinal sliding on said support, a thread carrying shuttle on the end of said carriage adjacent said body thread, means for sliding said carriage to move said shuttle to and fro across said 40 body thread, means for rocking said support upon its pivot to loop the shuttle thread around said body thread, and means for looping said shuttle thread in the path of 45 said shuttle.
10. In a machine for forming tatting braid, the combination of a thread carrying 50 shuttle adapted to carry its thread across one side of a body thread and back across the other side thereof to loop said shuttle thread around said body thread, a moving member for actuating said shuttle, holding means for both ends of said shuttle mounted on 55 said moving member, and means for alternately applying said holding means to opposite site ends of the shuttle.
11. In a machine for forming tatting braid, the combination of a thread carrying 60 shuttle adapted to carry its thread across one side of a body thread and back across the other side thereof to loop said shuttle thread around said body thread, a moving member for actuating said shuttle, a pair 65 of levers fulcrumed to said moving member and receiving said shuttle therebetween, shuttle holding means on said levers at opposite sides of their fulcrums, and means for rocking said levers to alternately hold and release each end of said shuttle.
12. In a machine for forming tatting braid, the combination of a thread carrying 70 shuttle adapted to carry its thread across one side of a body thread and back across the other side thereof to loop said shuttle thread around said body thread, a moving member for actuating said shuttle, a relatively fixed 75 support on which said moving member is mounted, a pair of levers fulcrumed to said moving member and receiving said shuttle therebetween, shuttle holding means on said levers on opposite sides of their fulcrums, 80 actuating means on said moving member for rocking said levers to alternately hold and release each end of the shuttle, and fixed means on said support to strike and operate 85 said actuating means.
13. In a machine for forming tatting braid, the combination of a thread carrying 90 shuttle adapted to carry its thread across one side of a body thread and back across the other side thereof to loop said shuttle thread around said body thread, a moving member for actuating said shuttle, a relatively fixed support on which said moving member is mounted, a pair of levers fulcrumed to said moving member and receiving 95 said shuttle therebetween, shuttle holding means on said levers on opposite sides of their fulcrums, an arm pivoted to said moving member and engaging the inner end of one of said pair of levers, an actuating 100 lever fulcrumed to said moving member and engaging the inner end of the other of said pair of levers, lateral projections on said actuating lever, one of said projections engaging said arm, and a trip mounted on said 105 support to strike the other projection and actuate said actuating lever.
14. In a machine for forming tatting braid, the combination of a thread carrying 110 shuttle adapted to carry its thread across one side of a body thread and back across the other side thereof to loop said shuttle thread around said body thread, a moving member for actuating said shuttle, front and rear sets 115 of shuttle holding detents mounted on said moving member, said shuttle having means to engage said detents, and means for alternately applying the two sets of detents.
15. In a machine for forming tatting braid, the combination of a thread carrying 120 shuttle adapted to carry its thread across one side of a body thread and back across the other side thereof to loop said shuttle thread around said body thread, a moving member for actuating said shuttle, front 125 and rear sets of shuttle holding plugs, said shuttle having sockets to receive said plugs, carrying means for said plugs, thread guards

extending from said carrying means on opposite sides of said plugs, and means for operating said carrying means to alternately move the two sets of plugs to operative position.

16. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, and means for operating said arm to loop said shuttle thread in the path of said shuttle.

17. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, a movable support for said arm, means for moving said support, and means for moving said arm in respect to said support, whereby to loop the shuttle thread in the path of the shuttle.

18. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, a movable support upon which said arm is pivoted, means for moving said support, and means for moving said arm on its pivot, whereby to loop the shuttle thread in the path of the shuttle.

19. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, a pivoted support on which said arm is mounted, means for moving said support on its pivot, and means for moving said arm in respect to said support, whereby to loop the shuttle thread in the path of the shuttle.

20. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, a pivoted support on which said arm is pivotally mounted, means for rocking said support upon its pivot, and means for

swinging said arm on its pivot, whereby to loop the shuttle thread in the path of the shuttle.

21. In a machine for forming tatting braid, the combination of means for supporting a body thread, a thread carrying shuttle movable across said body thread at one side thereof and movable reversely across said body thread at the other side thereof to loop the shuttle thread around said body thread, a thread manipulating arm, a lever to which said arm is pivoted, a second lever fulcrumed adjacent the fulcrum of said first named lever, a link connecting said arm and said second lever, and means for operating said levers to cause said arm to loop the shuttle thread in the path of the shuttle.

22. In a machine for forming tatting braid, the combination of means for supporting a body thread, a thread carrying shuttle movable across said body thread at one side thereof and movable reversely across said body thread at the other side thereof to loop the shuttle thread around said body thread, and a pair of thread manipulating arms for alternately moving the shuttle thread in different directions and looping it in the path of the shuttle.

23. In a machine for forming tatting braid, a table, means for supporting a body thread over said table, a thread carrying shuttle, a carriage for said shuttle, means for reciprocating said carriage horizontally to pass said shuttle to and fro across said body thread, a bracket rising from said table, a support for said carriage pivoted to said bracket for vertical swinging, means for alternately tilting said carriage support upwardly and downwardly to cause said shuttle to travel across the body thread at one side thereof and return on the other side of said thread, a thread manipulating arm supported by said table for looping the shuttle thread in the path of the shuttle, and operating means for said arm.

24. In a machine for forming tatting braid, a table, means for supporting a body thread over said table, a thread carrying shuttle, a shuttle carriage having a forked end loosely receiving said shuttle between the fork arms, a pair of levers fulcrumed to said fork arms and having front and rear shuttle holding means, a support for said carriage pivotally mounted on said table, means for reciprocating said carriage to move said shuttle to and fro across said body thread, coacting means on said carriage and carriage support for rocking said levers to alternately apply the front and rear shuttle holding means, means for alternately raising and lowering said carriage support to pass the shuttle alternately over and under the body thread, a thread manipulating arm mounted on the table for looping the

shuttle thread in the path of the shuttle, and means for operating said arm.

25. In a machine for forming tatting braid, the combination of means for supporting and guiding a body thread, means including a shuttle for looping thread on said body thread, feed means for said body thread and the looped thread thereon, and means synchronized with said shuttle for operating 10 said feed means.

26. In a machine for forming tatting braid, the combination of means for supporting and guiding a body thread, means including a shuttle for looping thread on 15 said body thread, a throw lever for actuating said shuttle, feed means for said body thread and the looped thread thereon, and an operating member for said feed means located in the path of said throw lever to be actuated 20 by the latter.

27. In a machine for forming tatting braid, the combination of means for supporting and guiding a body thread, means including a shuttle for looping thread on 25 said body thread, a throw lever for actuating said shuttle, feed means for said body thread and the looped thread thereon, a ratchet op-

eratively associated with said feed means, and a dog in the path of said throw lever to be actuated by the latter to operate said 30 ratchet.

28. In a machine for forming tatting braid, the combination of a thread carrying shuttle adapted to travel across a body thread at one side thereof and to return at the 35 other side of said thread to loop the shuttle thread around said body thread, a shuttle carriage, means for reciprocating said carriage to move the shuttle to and fro across the body thread, shuttle holding means at 40 spaced points on said carriage, a striker on said carriage and a fixed member coacting therewith to alternately apply said two holding means, a pivoted support on which said carriage is slidably mounted, means for alternately raising and lowering said support to direct the shuttle on opposite sides of the body thread, and thread manipulating arms for looping the thread alternately in the two 45 shuttle paths.

In testimony whereof I have hereunto set my hand.

HARRY H. WEST.
